UNITED STATES PATENT OFFICE

100,812

DESIGN FOR A TRAILER

John E. Coleman, Rosslyn, Va.

Application June 23, 1936, Serial No. 63,438

Term of patent 14 years

To all whom it may concern:

Be it known that I, John E. Coleman, a citizen of the United States, residing at Rosslyn, in the county of Arlington, State of Virginia, have invented a certain new, original, and ornamental Design for Trailers, of which the following is a specification, reference being had to the accompanying drawing, forming part thereof.

In the drawing,

What I claim is:

The ornamental design for a trailer substantially as shown.

JOHN E. COLEMAN.
